DESIGN FOR A FEMALE ELECTRIC PLUG

Jean Otis Reinecke, Oak Park, Ill., assignor to
Belden Manufacturing Company, Chicago, Ill.,
a corporation of Illinois

Application February 13, 1941, Serial No. 98,982

Term of patent 14 years

To all whom it may concern:

Be it known that I, Jean Otis Reinecke, a citizen of the United States, residing at Oak Park, county of Cook, and State of Illinois, have invented a new, original, and ornamental Design for a Female Electric Plug, of which the following is a specification, reference being had to the accompanying drawing, forming a part thereof.

Figs. 1, 2, and 3 are respectively top plan, side

elevational, and front elevational views of a female electric plug in accordance with my new design;

Fig. 4 is a bottom plan view of the plug; and
Fig. 5 is a perspective view thereof.

I claim:

The ornamental design for a female electric plug, substantially as shown.

JEAN OTIS REINECKE.
